tion of Delaware

Application January 26, 1933, Serial No. 653,561

2 Claims. (Cl. 200—35)

This invention relates to switches, and with regard to certain more specific features, to time-controlled electrical switches.

Among the several objects of the invention may be noted the provision of a time-controlled electrical switch which is, in effect, a single pole, double throw switch, with the time-control feature operative without regard to which of the two throws is used; a switch of the class described in which the elements are normally in a disconnecting position, and in which the time-control elements are brought into operation by the manual throwing of the switch to either of its connecting positions; a switch of the class described wherein the time-control elements effectively lock the switch in disconnecting position as soon as the elapsed time has equaled a pre-established amount, whereby the switch is incapable of being jarred into either connecting position; a switch of the class described which is particularly applicable to vehicle direction signal control; and the provision of a switch of the class described which is simple and economical of construction and operation. Other objects will be in part obvious and in part pointed out hereinafter.

The invention accordingly comprises the elements and combinations of elements, features of construction, and arrangements of parts which will be exemplified in the structures hereinafter described, and the scope of the application of which will be indicated in the following claims.

In the accompanying drawings, in which is illustrated one of various possible embodiments of the invention,

Fig. 1 is a front elevation of a switch embodying the present invention;

Fig. 2 is a side elevation of the switch of Fig. 1;

Fig. 3 is a back elevation of the switch of Fig. 1;

Fig. 4 is an enlarged back elevation of the switch of Fig. 1, certain cover portions being removed;

Fig. 5 is a cross section taken on line 5—5 of Fig. 4;

Fig. 6 is a cross section taken on line 6—6 of Fig. 4;

Fig. 7 is a horizontal cross section of the switch of Fig. 1 showing a timing train;

Fig. 8 is an ideal section taken along line 8—8 of Fig. 7; and,

Fig. 9 is a pictorial diagram illustrating the use of the switch of Fig. 1 as a vehicle direction signal control switch.

Similar reference characters indicate corresponding parts throughout the several views of the drawings.

Vehicle direction signals are coming into gen-

eral use at the present time. These signals operate in much the same manner as the now universally used "stop" lights on automobiles, with the exception that they indicate the direction in which the driver plans to turn instead of the driver's intention to slow down or stop. A difficulty with direction signals not encountered with stop signals, however, is that, in order to be effective as a warning to trailing cars, a direction signal must be given some time before the actual turn is commenced by the turning of the steering wheel, while with a stop signal, the operation of the automobile is such that the time interval between the time the brakes are applied and the actual stop is long enough for an automatic signal, operated synchronously with the braking system, to be effective. It is accordingly necessary with direction signals that some separate, signalling motion or action must be given by the driver before he takes the actual steps necessary to consummate his intention to turn. Thus, a separate control is needed. As most effective directional signals are electrically operated, the control logically takes the form of an electrical switch. This switch has heretofore been one of two types; either a momentary, or push-button affair which operates the signal only for an instant, or an ordinary two-position switch (stable on as well as stable off positions). A serious disadvantage of the first type is that it requires either a constant holding on by the driver from the time he first contemplates making the turn until the turn is consummated, thus removing at least one hand from the more essential manipulation of the steering wheel, or, if it is not manually held in on position, it makes a signal of so brief a duration that a trailing driver is likely to miss it altogether. A serious disadvantage of the second, two-position switch is that frequently the driver forgets that he has set it, say, for a left turn, and then, after the turn has been finished, the signal continues to the confusion of trailing drivers until chance recollection impels the driver to turn the signal off.

The present invention offers a switch which has the advantages of both of the types discussed, when used in a direction signal control system, and which at the same time eliminates the indicated disadvantages. Briefly, the switch of the present invention is a time-controlled switch which requires but an instant for actuation (in the manner of the push-button switch) but which, once actuated, remains on for only a predetermined time, then going off automatically. Thus, the driver is free, once he has

actuated the switch, to forget about his signal with the assurance that it will automatically go off in a few seconds (long enough to complete his turn).

5 The present invention has its particular applicability in the field of direction signal control systems, but it is not so limited in use. It is a desirable control wherever a selective switch with two selections is needed, either of the two selections to go on at the time the switch is actuated, and then to go off automatically a predetermined time thereafter.

10 Referring now more particularly to Fig. 1, numeral 1 indicates a housing or box, which is preferably formed of an insulating material such as a phenolic condensation product or the like. The casing 1 is open at its back. From the bottom of the casing 1, near the back thereof, a manipulating handle 2 projects. The handle 2 is movable either way from a center position, as indicated in Fig. 4. Two bolts 3 have their heads countersunk into the face of the housing 1, the bolts 3 serving as means for mounting the switch as will be seen hereinafter.

15 25 Covering the rear of the housing 1 is a cover plate 4 (Figs. 2 and 3) which may be cut from fiber or the like. The plate 4 is held in position by nuts 5 on the bolts 3. A central hold 6 passes the three wires for connections into the interior 30 of the switch.

20 35 Interiorly, the housing 1 is provided with shoulders 7 for mounting the elements of the switch proper (see Figs. 5, 6, and 7). The shoulders 7 are drilled as at numeral 8 to pass the mounting bolts 5 freely. The shoulders 7 are also drilled and tapped as at numeral 9 to receive mounting screws 10 for holding the switch proper in position (see Figs. 4 and 5).

30 40 Numeral 11 (Figs. 4, 5, and 6) indicates a brass or like metal plate upon which the various elements of the switch proper are mounted. The plate 11 conforms generally to the shape of the casing 1, and is mounted on the shoulders 7 by means of the screws 10. The mounting is a 45 particular feature of the present invention. As the switch includes a timing train and escapement (to be described), which produce the usual "tick-tick-tick" noise associated with clockwork, it is desirable that the mounting be such as to 50 minimize the noise. For this purpose (see Fig. 5) the screws 10 are flat headed and the holes in the plate 11 through which the screws 10 pass are countersunk to the shape of the screw heads. Between the screw heads and the plate 55 are provided rubber washers 12; similar rubber washers 13 are positioned between the plate 11 and the shoulders 7. The washers 12, it will be noted, are drawn to a conical shape as the screws 10 are drawn up. This combination of rubber washers floats the switch within its casing, and the noises of the escapement are absorbed to an appreciable extent.

60 65 Three terminals 14, 15 and 16 are mounted upon the plate 11. Terminal 14 comprises a simple bushing having a central threaded hole 17 therein, and upwardly terminated by a peripheral shoulder 18. The terminal 14 is in good electrical contact with the plate 11. Terminals 15 and 16, on the other hand, are electrically insulated from the plate 11 as shown in Fig. 6, by insulating washers 19 and 20. The terminals 15 and 16 also support oppositely directed arcuate springing contact arms 21 and 22, respectively, which arms are spaced up from the plate 11 to 70 avoid electrical contact therewith. The termi-

nals 15 and 16 have central threaded holes 17 and upper peripheral shoulders 18 in the same manner as the terminal 14.

75 80 The switch is desirably provided with a second fiber or like cover piece 23, which has suitable holes permitting it to rest on the shoulders 18 of the terminals 14, 15, and 16. Thus, on the outside of the cover 23, only the ends of terminal pieces 14, 15 and 16 are visible. Into the hole 17 of each terminal is threaded a screw 24, the three screws 24 constituting the binding posts by which wires are connected to the switch (see also Fig. 3).

85 90 Pivoted on a stud 25 mounted on the upper surface of the plate 11 is a control lever 26. The control lever 26 is preferably stamped or otherwise formed from sheet brass or the like, and has extending downwardly therefrom the manipulating handle 2. Upwardly, the lever 26 is formed with a camming edge 27, an arcuate portion 28, and a projection 29. The arcuate portion 28 is spaced so as to engage the arcuate springing contact arms 21 and 22, alternately, as the handle 2 is moved to its left and right hand positions, respectively. The width of the arcuate portion 28 is such that it can at no time be in contact with both arms 21 and 22.

95 100 It is by means of the lever 26 that electrical connections are made alternately and selectively to the terminals 15 and 16, constituting the "double throw" of the switch. This is because the lever 26 is in electrical connection with the plate 11, which is in turn in connection with the terminal 14, while the terminals 15 and 16 are insulated therefrom.

105 110 The apparatus thus far described constitutes the electric switching means proper of the invention. As forecasted, automatic timing means are provided for returning the switch to off position automatically, once it has been manually actuated to on position. The timing means are shown more in detail in Figs. 7 and 8.

115 120 Referring now more particularly to these figures, it will be seen that a mounting plate 30 of rectangular conformation is provided, the plate 30 fitting within the casing 1 below the point where the shoulders 7 project. The plate 30 is supported on the plate 11 by spacing columns 31, which are secured in position by bent-over fish-tail heads 32 (Fig. 4). Other spacing means 125 may of course be used.

130 135 Between the plates 11 and 30 are supported the various elements of a timing train and escapement mechanism. Numeral 33 indicates a main shaft, upon which is mounted, rotatably, a 140 collar 34. Upon collar 34 are mounted, immovably, a control bar 35, a clutch disc 36, and a 145 spring bearing plate 37. Rotation of the named elements is accordingly simultaneous. Also mounted on the collar 34, but in this instance rotatable relative to the collar, is a main gear 38.

150 155 The control bar 35 (Fig. 7) comprises a disc portion 39 having extending therefrom, at different radii, a pair of upright projections 40 and 41. The lower projection 40, which is at the shorter radius, extends and moves through an arcuate slot 42 in the plate 11, while the upper projection 41 similarly moves in an arcuate slot 43 in plate 11. The slots 42 and 43 are adjusted in length and position so that they both correspond to the same angle of rotation of the bar 35 as a whole. The projections 40 and 41 are sufficiently long to extend above the upper surface of plate 11 and engage the edges of lever 26, as will be described more fully hereinafter.

The main gear 38, which is rotatable on the collar 34, is of usual construction except that it is provided with a number of radial slots 44 (Fig. 7) spaced evenly therearound.

5 The clutch disc 36 is formed, preferably, of spring metal such as thin spring brass. It is generally of disc form (Fig. 7), but is so cut away as to leave three arcuate fingers 45 all facing in the same direction. The fingers 45 all have 10 turned-down ends 46 (Fig. 8) which are positioned to engage the slots 44 in main gear 38. The ends 46 are not turned down at right angles, but only at a slope of the order of 45°. This arrangement of slots 44 and fingers 45 is such 15 that, considering the combination from the direction represented by Fig. 7, when the clutch disc 36 is turned clockwise, the fingers 45 engage the slots 44 to carry the main gear 38 in coextensive clockwise rotation; but when the clutch disc 36 is turned counterclockwise, the fingers 45 override the slots 44 and the main gear 38 remains 20 stationary.

The spring bearing plate 37 is a disc, although it may take any suitable form, its function being 25 to hold, by means of an ear 47, one end of a coil spring 48 (Fig. 8), the other end of which is held by a suitable ear 49 struck up from the plate 30 38. The coil spring 48 is the main spring of the timing train, and it is initially tensioned so as to place a clockwise torque on the collar 34.

Engaging the main gear 38 is a pinion 39 supported on a shaft 51 having bearings in the plates 11 and 38. The shaft 51 also carries a large gear 52, which in turn engages a pinion 53 on an escapement wheel shaft 54. The shaft 54 carries an escapement wheel 55, which cooperates with an escapement mechanism indicated generally by numeral 56. The details of the escapement mechanism are of little consequence herein; they may 40 be found by reference to my co-pending application, Serial No. 572,917, filed November 4, 1931. Suffice it to say that the escapement mechanism permits only a slow, timed rotation of the escapement wheel 55, and hence, through the 45 gear reduction provided, an even slower, timed rotation of the main gear 38.

The operation of the timing mechanism is as follows:

When the control handle 2 is in central position, the projections 48 and 41 of the control bar 35 engage, respectively, the camming edge 27 of the lever 26 and the left-hand edge of its projection 28. In this position, which may be called the normal position of the switch, the timing train is still. The projections 48 and 41, held in position by the spring 48 and the friction of the timing train as a whole, serve to lock the lever 26 in said central position against jars, shocks and the like. In the central, normal position, the lever 26 is in contact with neither of the terminals 15, 16.

If, now, the handle 2 is thrown to its right-hand position (indicated by numeral 57 in dotted lines in Fig. 4), the lever 26 moves and carries with it the projection 41, thus rotating the control bar 35, and hence the collar 34, in a counterclockwise direction. Attendant upon the motion of the lever 26 is its contact with the terminal 16, completing the electrical circuit between terminals 70 14 and 16. If the handle 2 be thrown to the left (as indicated in dotted lines at numeral 58) instead of to the right, contact is made with terminal 15 in place of terminal 16; however, the rotation of the control bar 35 and collar 34 is still 75 counterclockwise, for it is now the engagement

of camming edge 27 with projection 40 which is impelling the control bar 35 to rotate. Thus, whichever way the handle 2 is thrown, the control bar 35 is rotated in the same direction, and through the same angular displacement. Mechanically, this is due to the arrangement provided whereby there is a driving element (lever 26) and a driven element (control bar 35) each rotating about its own center, with two points of engagement therebetween (projections 40 and 41), the points of engagement being on either side of the driving element and on either side of the center of rotation of the driven element (shaft 38), and the center of rotation of the driving element (stud 25) being outside of the line connecting the two points of engagement.

The reason for the camming edge 27, and for the fact that the projection 40 is at a shorter radius than the projection 41 from their common center, may be explained as follows: If the projections 40 and 41 were at the same radius, it is obvious that they would move at the same speed under influence of the timing train (albeit in opposite directions). Now, if the engagement of the projection 40 were with a simple tongue like 28 on the lever 26, and the radii of 40 and 41 were the same, the return of the lever from position 58 to neutral would be achieved only at a much slower speed than the return from position 58 to neutral, because projection 41, which moved at 30 the same speed as projection 40, is at a much greater distance from the center of rotation of the lever 26 than is projection 40. Compensation for the difference in distance between the projections 40 and 41 and the stud 25 is provided (1) 35 by the shorter radius of projection 40 from its own center of rotation 38, whereby it moves more slowly than the projection 41, and (2) by the camming edge 27, which by its design slows down the rotation of the lever 26 as occasioned by the 40 projection 40. Thus, in the device as shown, and assuming that the timing train always rotates the control bar 35 at the same angular speed, the lever 26 is returned to neutral position from either 45 extended position 57 or 58 in the same period of time.

It is thus seen that movement of the handle 2 in either direction rotates the control bar 35 in one direction at all times and through the same angular displacement. Now, it will be seen that 50 rotation of the control bar 35 also rotates the collar 34 and hence also the spring bearing plate 37. This winds, or imparts more tension into the coil spring 48, and the clockwise turning force on the collar 34 by said spring 48 increases. This 55 movement will hereinafter be termed the winding movement. By reason of the clutching arrangement described, between the clutch disc 36 and the main gear 38, the winding movement has no rotational effect on the main gear 38.

As soon as the manual force applied to move the handle 2 is removed, the spring 48 tends to commence rotating the collar 34 in a clockwise manner. However, the clutching means are now engaged, and the collar 34 cannot rotate without 65 at the same time rotating the main gear 38. But the main gear 38 can only rotate at a predetermined slow rate, because of the gear train and escapement 56. Thus, rotation of the collar 34 is held to a slow, timed speed, all under the influence of the spring 48. This is the timing control by which the switch is automatically returned to off position a predetermined time after it has been set to either on position. In returning to off position, the control bar 35 becomes the driv- 70 75

ing member, the lever 28 the driven member. Depending upon which way the handle 2 has been thrown, the driving is accomplished by either the projection 40 or the projection 41 (whichever of the two has functioned in the winding movement). Neutral position is achieved automatically, because the control bar 35 is positively locked against further rotation (and hence the escapement, etc., from further running) the instant both projections 40 and 41 are in engagement with their respective regions of lever 28.

It is thus seen that the switch is effectively a single pole, double throw type, with the movement to on positions manual and selective in either direction, and with the return to off position automatic and in a predetermined interval of time regardless of which of the two throws has been made.

20 The application of the switch for directional signal control is shown in Fig. 9. An automobile has been chosen as exemplary of the vehicle. Numeral 60 indicates the steering wheel, and 61 the steering column, whereon, for convenience, the switch 6 is desirably located. The directional signal is shown at numeral 62, and comprises a right-turn indicating arrow 63 and a left-turn indicating arrow 64. The arrows 63 and 64 are illuminated by suitable electric lamps, one terminal of each of which is grounded to the automobile chassis as by wire 65. The other terminal of the lamp corresponding to arrow 63 is connected by wire 66 to terminal 15 of the switch. The other terminal of the lamp corresponding to arrow 64 is likewise connected, by a wire 67, to terminal 16 of the switch. Terminal 14 of the switch is connected to one terminal of the automobile storage battery 68 by a wire 69; the other terminal of the storage battery is 40 grounded in the usual manner by a wire 70.

The operation of the switch in this arrangement is as follows: When a signal, say for a right turn, is desired, the driver throws the control handle 2 of the switch to the right as far as it will go. The right-turn arrow immediately illuminates. The driver then is able to disregard the switch entirely. The arrow stays illuminated for, say, sixty seconds, and then automatically goes off. The sixty second interval (or whatever 50 the time interval has been set for) represents adequate time to complete the turn. Then the switch is completely ready for its next manipulation. Jars and jolts to the automobile will not accidentally turn on either signal.

In view of the above, it will be seen that the several objects of the invention are achieved and other advantageous results attained.

As many changes could be made in carrying out the above constructions without departing from the scope of the invention, it is intended that all matter contained in the above description or shown in the accompanying drawings shall be interpreted as illustrative and not in a limiting sense.

10 I claim:

1. In a time-controlled switch, timing means, including a main shaft, adapted to be wound by rotation of said main shaft in one direction, and to unwind in a time-controlled manner rotating said main shaft in the opposite direction, manual control means having a neutral position and being rotatable on an axis parallel to that of the main shaft, in both directions from said neutral position, to establish different circuit conditions, means rotatable with said main shaft, said last-named means having two points of engagement with said control means when said control means is in neutral position, said points of engagement being spaced on opposite sides of said control means and on opposite sides of the center of rotation of said main shaft, and the center of rotation of said control means being outside the line connecting said points of engagement.

2. In a time-controlled switch, timing means, including a main shaft, adapted to be wound by rotation of said main shaft in one direction, and to unwind in a time-controlled manner rotating said main shaft in the opposite direction, manual control means having a neutral position and being rotatable on an axis parallel to that of the main shaft, in both directions from said neutral position, to establish different circuit conditions, means rotatable with said main shaft, said last-named means having two points of engagement with said control means when said control means is in neutral position, said points of engagement being spaced on opposite sides of said control means and on opposite sides of the center of rotation of said main shaft, and the center of rotation of said control means being outside the line connecting said points of engagement, one of said points of engagement being at a shorter radial distance from said center of rotation of said main shaft than the other point of engagement.
